US0D1074466S

(12) **United States Design Patent** (10) Patent No.: **US D1,074,466 S**
(45) Date of Patent: ** May 13, 2025

(54) **TEMPERATURE CONTROLLER FOR ELECTRIC MATS**

(71) Applicant: **KYUNG DONG NAVIEN CO., LTD.**, Pyeongtaek-si (KR)

(72) Inventors: **Ji Seok Heo**, Seoul (KR); **Kyu Young Lee**, Seoul (KR)

(73) Assignee: **KYUNG DONG NAVIEN CO., LTD.**, Pyeongtaek-si (KR)

(**) Term: **15 Years**

(21) Appl. No.: **29/900,759**

(22) Filed: **Aug. 24, 2023**

(30) **Foreign Application Priority Data**

Apr. 27, 2023 (KR) 30-2023-0016404

(51) **LOC (15) Cl.** **10-04**

(52) **U.S. Cl.**

USPC **D10/50**; D14/218

(58) **Field of Classification Search**

USPC D10/49, 53, 51, 47, 50, 52, 60, 78;

D14/358, 205

CPC A61F 2007/0086; A61F 2007/0087

See application file for complete search history.

(57) **CLAIM**

The ornamental design for a temperature controller for electric mats, as shown and described.

DESCRIPTION

FIG. 1 is a perspective view of a temperature controller for electric mats, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The word "NAVIEN" is a registered trademark of KYUNG-DONG NAVIEN CO., LTD., which does not form part of the claimed design.
